UNITED STATES PATENT OFFICE.

WINFIELD S. GILMORE, OF NEW YORK, N. Y.

PACKAGE-CARRIER.

SPECIFICATION forming part of Letters Patent No. 700,323, dated May 20, 1902.

Application filed February 19, 1902. Serial No. 94,736. (No model.)

To all whom it may concern:

Be it known that I, WINFIELD S. GILMORE, a citizen of the United States, and a resident of New York city, in the county and State of New York, have invented certain new and useful Improvements in Package-Carriers, of which the following is a specification.

This invention relates to a package-carrier adapted to carry papers and packages of various kinds. Such package-carrier is designed more particularly to be used in connection with any one of the well-known parcel-carrying systems such as are used in stores or offices; but it is especially designed for use in connection with a pneumatic-despatch-tube system. In some of the pneumatic-tube systems the tubes lead from individual stations to a central or distributing station. Packages sent from one individual station to another individual station are inclosed in the carrier and sent to the main station, where they are received and transferred to the tube leading to the desired destination.

The present invention seeks more particularly to provide convenient, reliable, and inexpensive means for clearly indicating the destination of the carrier, whereby the speedy arrival of the carrier at its proper destination may be insured.

This invention consists of the construction hereinafter set forth.

In the accompanying drawings, forming part of this specification, and in which like reference-numerals designate corresponding parts, Figure 1 is a central sectional elevation on the line 11 of Fig. 2. Fig. 2 is an end elevation looking in the direction of the arrow in Fig. 1.

Referring now more particularly to the details of the invention, especially as illustrated in the drawings, 1 is a container in the form of a cylindrical tube having the closed end 2 and having at the opposite end a closure 3. This closure consists of the plate 4, secured to the container by the hinge 5 and provided with a handle 6 for opening and closing the same. The handle 6 consists of a bar, preferably made of wood and clamped in place by the bolt 7, which passes through the plate 4 and the handle.

8 is a lug by means of which the closure is latched in closed position. The closure 3

carries an adjustable station-indicator by means of which the destination of a carrier may be known. In this indicator there is a plate having a series of station characters marked thereon and an apertured disk fixed over said plate, said plate and disk being relatively adjustable, so as to display through the aperture of the latter any character on the former. In the present embodiment of the invention this indicator consists of a series of station characters marked in a circle on the outer face of the plate 4 and a disk 9, adapted and designed to display any one of such station characters, as may be desired. As shown in Fig. 2, these station characters are numerals. In the present embodiment of the invention the disk 9 is provided with an aperture 10 near its margin and is capable of rotating on the plate 4, so as to display through the aperture 10 any one of the station-numerals desired. The bolt 7 passes through the disk 9 and clamps this disk between the handle 6 and the plate 4. When the handle 6 is turned, the disk 9 rotates with it. Thus the handle is common to the closure and the indicator. The disk 9 is provided with a notch 11, which in the present form is in the same radial line as the aperture 10. When the closure is moved from a closed position to open position, or vice versa, the lug 8 passes through the notch 11. When the closure has been moved into closed position, as shown in Fig. 1, and the disk 9 has been turned to display any one of the station characters desired, the notch 11 then moves out of register with the lug 8, and the closure is thus latched in closed position, but permitting the indicator to be adjusted so as to display any station character desired. In the present embodiment of the invention the disk 9 is slightly larger in diameter than the plate 4, so that when the closure is in closed position the plate 4 fits within the container and the disk 9 fits against the end of the wall of the container. This is shown in the drawings.

12 is a notch formed in the margin of the plate 4 to permit the passage of the lug 8 when the closure is moved from one position to another.

It is not of course essential that the station characters be marked on the plate 4 itself, and various other changes which will readily

occur to any one skilled in the art may be made without departing from the scope of the invention.

13 and 14 are two bands of sheep's wool, entering 5 circling the container at its end to constitute packing-rings.

The numeral 15 on the face of the disk 9 indicates the home station of the carrier and enables the carrier to be promptly returned to its home station when its errand has been performed. Each of the various carriers in use is thus marked with a numeral or character to indicate its own home station.

What I claim, and desire to secure by Letters Patent, is—

1. In a package-carrier the combination of a container; a hinged closure therefor at one end; a station-indicator carried by said closure and consisting of a plate having station characters thereon, and an apertured disk rotatably mounted on said plate; and means for locking the closure by the rotation of said disk.

2. In a package-carrier the combination of a container; a hinged closure therefor at one end; a station-indicator carried by said closure and consisting of a plate having station characters thereon, and an apertured disk rotatably mounted on said plate; means for locking the closure by the rotation of said disk; and a common handle for the closure and for the indicator.

3. In a package-carrier the combination of a cylindrical container; a circular hinged closure therefor at one end; a station-indicator carried by said closure, said indicator consisting of a series of station characters marked on said closure, and an apertured circular disk rotatably mounted on the closure so as to expose any given station character through its aperture, and having a notch in its periphery; an inwardly-projecting lug on the container at its closure end and designed to pass through the notch in said disk when the closure is moved into closed position and, when the said disk is thereafter rotated, to hold the closure in closed position.

4. In a package-carrier the combination of

a cylindrical container; a circular hinged closure therefor at one end and arranged to fit within the end of said container; a station-indicator carried by said closure, said indicator consisting of a series of station characters marked on said closure, and an apertured circular disk rotatably mounted on the closure so as to expose any given station character through its aperture, said disk being slightly larger in diameter than the closure, and having a notch in its periphery; an inwardly-projecting lug on the container at its closure end and designed to pass through the notch in said disk when the closure is moved into closed position and, when the said disk is thereafter rotated, to hold the closure in closed position.

5. In a package-carrier the combination of a cylindrical container; a circular hinged closure therefor at one end; a station-indicator carried by said closure, said indicator consisting of a series of station characters marked on said closure, and an apertured circular disk rotatably mounted on the closure so as to expose any given station character through its aperture, and having a notch in its periphery; an inwardly-projecting lug on the container at its closure end and designed to pass through the notch in said disk when the closure is moved into closed position and, when the said disk is thereafter rotated, to hold the closure in closed position; and a common handle for the closure and for the indicator.

6. In a package-carrier the combination of the cylindrical container 1; a hinged closure-plate 4 having station characters thereon; an apertured disk 9 having a notch 11; a lug 8; a handle 6 and bolt 7, substantially as set forth.

In testimony whereof I have signed my name to this specification in the presence of two subscribing witnesses.

WINFIELD S. GILMORE.
